UNITED STATES PATENT OFFICE.

ZAVERIO REVIGLIO DELLA VENERIA, OF TURIN, ITALY.

CIRCUIT-CHANGING SWITCH.

1,410,855.

Specification of Letters Patent. Patented Mar. 28, 1922.

Application filed August 11, 1920. Serial No. 402,772.

To all whom it may concern:

Be it known that I, ZAVERIO REVIGLIO DELLA VENERIA, a subject of the King of Italy, and resident of Turin, Italy, have invented certain new and useful Improvements in Circuit-Changing Switches; and I do hereby declare the following to be a full, clear, and exact description of the invention, such as will enable other skilled in the art to which it appertains to make and use the same, reference being had to the accompanying drawings, and to letters or figures of reference marked thereon, which form a part of this specification.

15 This invention relates to a device for interrupting, commutating, reversing and deviating the electric current characterized chiefly by the fact that the contact springs are dispensed with and the snap mechanism is greatly simplified.

20 The chief advantages obtained by this invention are:

The switching on and off is effected instantaneously by a snapping operation. The construction is very simple and economical as the device is constituted by the smallest possible number of pieces and may be of any suitable insulating material without a great mechanical precision being necessary.

25 Moreover the device may be used for any kind of plant and there are only two points of contact between the members to be connected or disconnected.

In the annexed drawing is shown by way of example a constructional form of this device.

Fig. 1 is a longitudinal section on line A, B, Fig. 2.

Fig. 2 is a plan view of the switch base with the contact plates.

Fig. 3 is a diagrammatic view of a plant. On the switch base 1 of insulating material are secured two pairs of metallic plates 3, 3' 3' forming a ring kept in place by means of pins 4, 4' 4' acting as terminals. The plates 3 project from the base to which they are secured and at the ring interruption points 6, 6' the plate edges are articulated (see Fig. 2).

50 The switch cover 7 is bell-shaped in order to fully protect the contact plates. Said cover is of insulating material and is provided internally with a pin 2 having a threaded end and secured by means of a nut 55 to the base 1.

Inside the cover 7 loosely mounted on the

pin 2 is a disc 16 and between this latter and the cover is arranged a spiral spring 11, the ends of which are secured at 12 to the cover and at 13 to the disc 16. Between the disc 60 16 and the contact plates are mounted two metallic balls 5 situated in two diametrically opposite cavities 16' formed in the disc 16. The spring 11 acting on the disc 16 holds the balls 5 constantly forced upon the contacts 3.

As will be seen from Fig. 2 of the drawing, the plates 3, 3 are connected with similar poles, and the plates 3', 3' also to similar poles, but opposite to those of the first 70 two plates. Assuming the switch to be in the resting position (that is the balls being in the spaces 6 of the contacts) the circuit will be open as each ball connects poles of the same sign.

75 Of course when the device is used as interruptor, it may be sufficient to connect a single plate 3 with one of the line poles and a single plate 3' (adjacent to the plate 3) with the pole of opposite sign (see diagram 80 of Fig. 3, right hand side).

By causing the cover to rotate, the spring 11 will be wound or unwound till it is sufficiently tensioned to force the balls 5 out of the cavities 6 and by overcoming the inclination of the plates 3 said balls will be brought instantaneously into the cavities 6', thus connecting the plates of opposite sign and closing the circuit.

The above described device may be used 90 without changing its construction but simply varying the relative position of the balls or line connexions for all kinds of plan designs.

101 shows an application as ordinary interruptor for a lamp or group of lamps (111).

102 shows an application as deviator in order to switch on or off a lamp or group of lamps (112) from two different points. 100

103 shows the device used as a switch to turn on two lamps or groups of lamps (113) at the same or different time.

104 shows an application as double deviator to switch on or off a lamp or group 105 of lamps (114) from more than two points.

In the diagram, 110 indicates the main line.

Evidently the balls could be substituted by similar members of a different form movable or fixed to the disc; in this latter case there will be the further advantage of hav-

ing a single spring for the snap operation and the contact pressure.

What I claim is:

In a circuit changing switch, an insulating base, a series of contacts comprising metallic plates arranged on the base in circular formation and having arcuate ends forming spaces between the plates, one or more of said plates being electrically connected to like poles and one or more to poles opposite to

the former poles, a pin axially projecting from the base, an insulating disc on the pin, spherical contacts interposed between the disc and plates, an insulating cap covering the disc and plates, and a spring connected to the cap and disc for pressing the latter onto the spherical contacts. 15

In testimony that I claim the foregoing as my invention, I have signed my name.

ZAVERIO REVIGLIO DELLA VENERIA.
